UNITED STATES PATENT OFFICE.

CHARLES A. DALEY AND JOHN LYNDALE, OF MINNEAPOLIS, MINNESOTA; SAID DALEY
ASSIGNOR OF ONE-HALF OF THE WHOLE RIGHT TO ROBERT H. CARLSON, OF MINNE-
APOLIS, MINNESOTA.

RETURN-FEED ATTACHMENT FOR WOODWORKING-MACHINES.

1,288,845.

Specification of Letters Patent. Patented Dec. 24, 1918.

Application filed June 5, 1917. Serial No. 172,967.

To all whom it may concern:

Be it known that we, CHARLES A. DALEY and JOHN LYNDALE, citizens of the United States, residing at Minneapolis, in the county 5 of Hennepin and State of Minnesota, have invented new and useful Improvements in Return-Feed Attachments for Woodworking-Machines, of which the following is a specification.

10 This invention relates to wood working machines such as jointers and the like and it has for its object to provide a device which may be described as a return feed attachment whereby the planks or pieces of 15 material operated upon will be automatically returned to the jointer or other machine to which the present invention forms an attachment.

20 A further object of the invention is to produce a return feed attachment of simple and improved construction including means whereby the plank will be automatically reversed or turned over before being returned to the jointer or other machine.

25 With these and other ends in view which will readily appear as the nature of the invention is better understood the same consists in the improved construction, arrangement and combination of parts which will be 30 hereinafter fully described and particularly pointed out in the claims.

In the accompanying drawings has been illustrated a simple and preferred form of the invention; it being understood that no 35 limitation is necessarily made to the precise structural details therein exhibited but that changes, alterations and modifications within the scope of the appended claims may be resorted to when desired.

40 In the drawings.

Figure 1 is a side elevation of a device constructed in accordance with the invention.

Fig. 2 is a top plan view of the same.

45 Fig. 3 is a bottom plan view, the legs or supports being shown in section.

Fig. 4 is a longitudinal vertical sectional view taken on the line 4—4 in Fig. 2.

50 Fig. 5 is a sectional detail view taken on the line 5—5 in Fig. 2.

Fig. 6 is a sectional detail view taken on the line 6—6 in Fig. 2 and showing the dog in an intermediate position between the lim-

its of its movements, and a portion of a plank engaging the same. 55

Fig. 7 is a sectional detail view taken on the line 7—7 in Fig. 3.

Fig. 8 is a perspective view of the timer, the component parts thereof being separated.

Fig. 9 is a transverse sectional view taken 60 on the line 9—9 in Fig. 3, and showing a plank on the table ready for turning.

Fig. 10 is a transverse sectional view similar to Fig. 9 and showing the plank turning table raised and the plank turned. 65

Fig. 11 is a sectional detail view taken on the line 11—11 in Fig. 2.

Corresponding parts in the several figures are denoted by like characters of reference.

The bed frame A which is supported on 70 legs 15, includes side members 16 on which longitudinal guide flanges 17 are adjustably mounted, said guide flanges having been shown as being provided with lugs 18 having slots 19 engaged by clamping screws 20. 75 While the distance between the guide flanges 17 may be varied, said flanges are to be always preserved in substantially parallel relation to each other and also to the side walls 21 of a casing C supported at the 80 front end of the frame, this being the end at which planks are initially received from the jointer or other machine and at which said planks are subsequently discharged in the direction of such machine. 85

The casing C has an end wall 22 supporting a crosshead 23 affording bearings for a driving shaft 24 and a main operating shaft 25 which latter receives motion from the driving shaft 24 by suitable transmission means such as gear wheels 26, 27 both meshing with an intermediate idler 28. The shaft 24 may be driven from any convenient source of power, such as a moving part of the jointer or other machine not 90 shown, to which the present invention forms an attachment. 95

The shaft 25 carries a feed drum 28 the face of which is provided with spikes 29 that project at diametrically opposite sides 100 through slots 30 in the side walls 21 of the casing C. The guide flanges 17 are provided at diametrically opposite sides of the feed drum 28 with slots 31 for the accommodation of presser wheels 32 which 105 are supported for rotation on pivoted arms

33 which, by springs 34, are pressed in the direction of the feed drum, thereby causing material such as planks passing between the guide flanges 17 and the side walls 21 5 to be forced resiliently in the direction of the latter and of the feed drum by the spikes of which the material will be engaged and fed in the proper direction, the direction of rotation of the feed drum being indicated by an arrow.

The passage ways between the flanges 17 and the side walls 21 at the two sides of the machine are designated respectively by 15 35 and 36 as best seen in Fig. 2, the passage way 35 being the one in which material is received as it comes from the jointer or other machine and the passage way 36 being the one through which material is discharged in the direction of the jointer 20 after having been subjected to the operation of the present machine. These passage ways may be regarded as extending the full length of the machine, as do the flanges 17, said passage ways being bounded only for a portion 25 of their respective lengths by the side walls 21.

The bottom of the passage way 35 is provided with a longitudinal slot 37 the side walls of which are provided with recesses 30 forming spaced enlargements or openings 38, 39. This slot with its enlargement is for the accommodation of a reciprocating slide or carriage which will for convenience be called the dog D and which comprises a 35 body member or plate 40 having perforated ears or lugs 41 whereby it is slidably mounted on the track bar or rod 42, said body member serving to support a dog 43 which is pivotally connected therewith by a pin or pivot member 44. The dog 43 has a head 45 which is considerably wider than the body of the dog but which is capable of passing through the enlarged portions 38, 39 of the slot 37. Said dog is also provided with stop members 46, 47 adapted to limit the pivotal movement thereof by engagements respectively with the body member 40 and with the end face of one of the ears or lugs 41, see dotted lines in Fig. 5. The dog 43 is also provided 45 with a laterally extending lip or flange 48 for engagement with the actuating springs 49, 50, the latter being curved springs which are supported adjacent to the ends of the slot 37 and which extend in the direction of 55 each other as best seen in Figs. 5 and 6. The spring 49 normally engages the flange 48, thus supporting the dog 43 with its head 45 projecting upwardly through the enlarged portion 38 of the slot 37, and in the path of 60 material coming from the jointer, in which position the timer D is normally sustained by the action of a retracting member such as a weight 51 which is connected with the timer by a suitable guide flexible element or 65 cord 52.

Between the side members 16 of the bed frame in rear of the casing C there is a rectangular opening 53 which is normally obstructed by a plate or table 54 which is connected with one of the side members, adjacent to the passage way 36, by means of hinges 55, enabling said table to tilt upwardly as clearly seen in Fig. 10 of the drawings. The tilting mechanism of the table includes a resilient arm or bar 56 one 75 end of which is firmly secured to the under side of one of the frame members 16 adjacent to the free edge of the table, the free end of said resilient arm bearing against a block 57 on the under side of the table 54 80 adjacent to the hinged edge thereof. It is obvious that pressure in an upward direction exerted on the resilient arm 56 will serve to tilt the table 54 to the position shown in Fig. 10. For the purpose of automatically restoring the table 54 to a closed position, the under side of said table is provided with an arm 88 carrying a weight 87.

To actuate the arm 56 the following instrumentalities are provided:

Supported for rotation beneath the bed frame and below the table 54 is a shaft 58 having at one end a bevel pinion 59 meshing with a bevel gear 60 carried by the shaft 25 below the feed drum 28. The shaft 58 which is thus constantly driven when the machine is in operation, carries a dentate wheel 61, which is fixed thereon, said dentate wheel being adapted for engagement with a spring actuated pawl or dog 62 which is pivoted on 100 a flange 63 extending from an eccentric cam 64 which is loosely mounted on the shaft 58, the latter being provided with a set collar 65 to limit the endwise movement of the eccentric cam. The tendency of the actuating 105 spring 66 is to maintain the dog 62 in engagement with the dentate wheel 61. The dog however is provided with a lip 67 lying in the path of a stop member which consists of a rod 68 carried by a slide 69 which is normally actuated in the direction of the dog carrying flange 63 by means of a spring 70. The slide 69 may be retracted against the tension of the spring 70 by means of a lever 71 fulcrumed at 72, said lever having a slot 115 73 engaging a pin 74 that projects from the slide 69 and said lever having an arm 75 provided with a keeper 76 engaging a pin or stud 77 that projects from a longitudinal 120 slidable rod 78 one end of which as will be best seen in Fig. 3, is disposed in the path of the dog D.

A transversely disposed shaft 79 is provided with a bevel pinion 80 meshing with the bevel gear 60 whereby the shaft 79 will 125 be constantly driven when the machine is in operation. The shaft 79 carries a pulley 81 over which is trained an endless conveyer 82, said conveyer being also guided over an idler 83, the upper lead of said conveyer being 130

guided over the bottom of a portion of the passage way 36 said upper lead obviously moving in the direction of the front end of the device where material is received and 5 delivered.

Secured on the inner face of the flange 17 which constitutes one side wall of the passage way 35 is a ledge 84 which is positioned a short distance below the lower 10 edge of the flange 17 and which is of a width to afford a partial support for a piece of material such as a plank moving in the passage-way, said ledge 84 extending over the enlarged portion 37 as far as may be desired. 15 One of the frame members 16 is provided, adjacent to the front edge of the ledge 84, with a small supporting plate 85, lying in the same horizontal plane as the ledge 84, and coöperating with the latter to tempor- 20 rarily support the plank passing through the passage way 35. It will be readily understood that as soon as such plank passes out of engagement with the supporting mem- 25 ber 85, it will gravitationally tilt and fall from the ledge 84 upon the table 54 where it will be momentarily supported. It will of course be premised that the plank or piece of material coming from the jointer or other machine is standing on one edge as 30 it passes through the passage way 35. As it drops on the table 54 it will lie on one side, and when said table is uplifted the plank will again be placed on edge on the endless conveyer 82, it having been inverted 35 ed by the tilting operation as described.

From the foregoing description taken in connection with the drawings hereto annexed the operation and advantages of this invention will be readily understood. A 40 plank entering the passage way 35 at the front end of the machine will strike the head 45 of the dog which projects upwardly through the enlarged portion 38 of the slot 37 in which position the head is normally 45 held by action of the spring 49 against the flange 48 of the dog 43. As the plank is moved along the passage way by the drum 28, the dog is carried forward along with it, the flange 48 being engaged by the spring 50 whereby downward pressure is exerted on the dog, the latter being tilted down- 55 wardly until the head 45 passes through the enlarged portion 39 of the slot 37. That portion of the bottom member of the passage way which extends between the openings 38 and 39 is terminally beveled as seen at 86 in Fig. 5, permitting the head 45 to slide beneath said bevel ended portion, the dog being retracted by the weight 51, until the 60 head 45 lies beneath the opening 38, the flange 48 being engaged by the spring 49 the tension of which is exerted upwardly thereagainst. Thus the dog moves forward and down then rearward and up. The dog 65 43 will not however be restored to its ini-

tial position until the plank passes beyond the opening 38 and out of the path of the head 45 which will now be projected upwardly by the action of the spring 49. The plank will be moved by the feed wheel in 70 a rearward direction until it rests on the ledge 84 and the supporting member 85, and in this position it will remain until the second plank enters the machine when the first will be pushed out of engagement with the 75 supporting member 85 and will tilt or drop sidewise on the table 54. At the same moment the rod 78 will be engaged by the dog and moved longitudinally in a rearward direction thereby actuating the lever 71 whereby the slide 69 is retracted against the tension of the spring 70. The stop member 68 will thus be moved out of the path of the spring actuated dog 62 which latter will instantly engage the ratchet wheel 61, thus 80 causing the cam member 64 to be carried around with the wheel 61 about the axis of the shaft 58. During the period of rotation the cam member 64 will exert upward pressure against the resilient arm 56 where- 85 by the table 54 will be tilted upwardly to deposit the plank in an inverted position on the endless conveyer 82. As the cam mem- 90 ber 64 passes out of engagement with the re- silient arm 56 the table 54 will be restored 95 to its initial position by the weight 88 and will thus be ready for a repetition of the op- 95 eration while the inverted plank is carried by the conveyer 82 into engagement with the feed drum 28 by the action of which it 100 is discharged.

Having thus described the invention what is claimed is:—

1. A bed frame having longitudinal pas- 105 sage ways at the two sides thereof, a tilting table intermediate said passage ways to transfer material from one passage way to the other, upright flanges constituting the outer side walls of the passage ways, means for conveying material in opposite direc- 110 tions through the opposite ways, and a nar- row ledge mounted on the side wall of the passage way adjacent to the free edge of the table.

2. A bed frame having longitudinal pas- 115 sage ways at the two sides thereof, means for conveying material in opposite direc- 120 tions through the two passage ways, a tilting table hinged adjacent to one passage way and having a free edge supported ad- jacent to the other passage way, upright flanges constituting the outer side walls of the two passage ways, a narrow ledge sup- 125 ported on the side wall adjacent to the free edge of the table to afford a partial support to material in the passage way, and a sup- porting member adjacent to and spaced from the ledge at the receiving end of the latter said supporting member being of small extent so that material passing out of 130

engagement therewith will drop gravitationally on the ledge of the table.

3. A bed frame having longitudinal passage ways at the two sides thereof, means 5 for conveying material in opposite directions through the two passage ways, a tilting table hinged adjacent to one passage way and having a free edge supported adjacent to the other passage way, upright 10 flanges constituting the outer side walls of the two passage ways, a narrow ledge supported on the side wall adjacent to the free edge of the table to afford a partial support to material in the passage way, and a sup- 15 porting member adjacent to and spaced from the ledge at the receiving end of the latter said supporting member being of small extent so that material passing out of engagement therewith will drop gravita- 20 tionally on the ledge of the table; in combination with means whereby the table will be tilted at stated intervals to transfer material deposited thereon to the passage way adjacent to the hinged edge of the table.
- 25 4. A bed frame having longitudinal passage ways at the two sides thereof, means for conveying material in opposite directions through the two passage ways, a tilting table hinged adjacent to one passage 30 way and having a free edge supported adjacent to the other passage ways, upright flanges constituting the outer side walls of the two passage ways, a narrow ledge supported on the side wall adjacent to the free 35 edge of the table to afford a partial support to material in the passage way, and a sup- porting member adjacent to and spaced from the ledge at the receiving end of the latter said supporting member being of 40 small extent so that material passing out of engagement therewith will drop gravita- tionally on the ledge of the table; in combi- 45 nation with means whereby the table will be tilted at stated intervals to transfer ma- terial deposited thereon to the passage way adjacent to the hinged edge of the table, and a driven endless conveyer operating in the last mentioned passage way.

5. A bed frame having longitudinal passage ways at the two sides thereof, a tilting 50 table arranged intermediate the passage ways and hinged adjacent to one passage way, a feed drum for feeding material in opposite directions in the two passage ways, tilting means for the table including a bearing block on the under side adjacent to the hinged edge thereof, a securely supported resilient arm engaging said bearing block, a cam supported for rotation and adapted to engage the resilient arm and means for 60 actuating said cam at stated intervals.

6. A bed frame having longitudinal passage ways at the two sides thereof, a tilting table arranged intermediate the passage ways and hinged adjacent to one passage 65 way, a feed drum for feeding material in opposite directions in the two passage ways, tilting means for the table including a bearing block on the underside adjacent to the hinged edge thereof, a securely supported 70 resilient arm engaging said bearing block, a cam supported for rotation and adapted to engage the resilient arm and means for including a trip device and a timer actuatin- 75 g the same.

7. A bed frame having longitudinal passage ways at the two sides thereof, a tilting table arranged intermediate the passage ways and hinged adjacent to one passage way, a feed drum for feeding material in 80 opposite directions in the two passage ways, tilting means for the table including a bearing block on the under side adjacent to the hinged edge thereof, a securely supported resilient arm engaging said bearing block, 85 a cam supported for rotation and adapted to engage the resilient arm and means for including a trip device and a timer actuatin- 90 g the same; said table being provided with a weight carrying arm to restore it being tilted upwardly.

In testimony whereof we affix our signatures.

CHARLES A. DALEY.
JOHN LYNDALE.
